APPARATUS FOR CHARGING SIPHON BOTTLES

Oscar A. Knable, Lakewood, and Clarence N. Mertes, Berea, Ohio, assignors to General Dry Batteries, Inc., Cleveland, Ohio, a corporation of Ohio

Application February 18, 1939, Serial No. 257,236

17 Claims. (Cl. 226—62)

This invention relates to an apparatus for charging and recharging siphon bottles with carbonated water and free gas.

Carbonated water is usually dispensed and sold in so-called siphon bottles and such bottles have usually been filled or charged in plants where expensive equipment is provided. The cost of collecting and distributing such bottles has therefore been an important factor. Usually neighborhood stores such as drug stores have carbonating equipment, that is, equipment for making carbonated water and could therefore refill or recharge such siphon bottles at a very small cost if they had available a suitable inexpensive filling device thereby greatly reducing the cost of such siphon bottles to the consumer.

It is therefore an object of this invention to provide a suitable filling device for charging and recharging such siphon bottles which occupies a very little space and which is well adapted for the purpose intended.

As the amount of carbon dioxide gas which water will absorb and retain is almost directly proportional to the temperature of the water, a considerable amount of gas frees itself from the water and accumulates in the upper part of the siphon bottle when the temperature of the water is elevated to any great extent. In charging or refilling siphon bottles with carbonated water it is customary to fill the bottle only about three-fourths full. The invention herein described contemplates first charging the siphon bottle with a predetermined quantity of carbonated water and then charging the bottle with an additional amount of free gas. The carbonated water with which the bottle is first charged has absorbed therein a substantial amount of gas but if the bottle and its contents are substantially cooled, the water will tend to absorb an additional amount of free gas due to the fact that the temperature of the water has been decreased and also due to the fact that the free gas in the upper portion of the siphon bottle is at a pressure of the order of 125 pounds per square inch. This free gas being under considerable pressure also aids in dispensing the carbonated water from the bottle at considerable pressure until all of the water has been dispensed from the bottle.

Specifically the invention comprises an apparatus for first charging or recharging the bottle with carbonated water and then charging the bottle with an additional quantity of free gas at considerable pressure. The apparatus consists essentially of a dispensing head which includes a pair of discharge outlets through which

carbonated water and gas may be discharged. It is customary to charge siphon bottles through the discharge spout thereof. The apparatus herein disclosed has two dispensing outlets which are disposed closely adjacent each other and are shaped to receive therein the delivery end of the discharge nozzle of the dispensing bottle. A single lever is also provided for positioning and holding the siphon bottle first in the position to be charged with carbonated water and then in a position to be charged with free gas. Carried by the lever is a device for opening the siphon bottle dispensing valve so as to permit the bottle to be charged through the discharge spout thereof.

The dispensing head is provided with a pair of valves for controlling the delivery of carbonated water and free gas. These valves are positioned so as to be actuated by the dispensing nozzle of the siphon bottle to open the same. The entire filling device is simple and compact in construction and comprises very few parts which are well adapted for production at comparatively low cost.

Further and more limited objects of the invention will appear as the description proceeds and by reference to the accompanying drawing in which Fig. 1 is a perspective view showing our improved apparatus attached to a counter or bar; Fig. 2 is a vertical sectional view on the line 2—2 of Fig. 1; and Fig. 3 is a view in side elevation showing a siphon bottle in the position in which it will appear when being charged.

Referring now to the drawing, the charging apparatus consists essentially of a supporting member 1 which is adapted to have one end secured to the under side of a counter or bar 2, the opposite end being disposed at an angle and having an enlarged head portion which is shaped in section, as shown most clearly in Fig. 2. The supporting member 1 is preferably in the form of a die casting and has formed thereon a strengthening rib 3. Secured to the supporting member 1 and extending upwardly therefrom is a post 4 which is interiorly threaded and is secured in place by means of a screw or bolt 5. Adjustably secured to the post 4 and extending outwardly therefrom is an arm 6 which is held in the adjusted position by a set screw 7. Pivottally secured to the outer end of the arm 6 is an arm 8, which is also preferably formed of a die casting, and has formed thereon a head member 9 having therein a pair of sockets or openings 10 and 11 each of which receives therein a rubber cap or sleeve 12. Pivottally secured to the arm 8 is a

- lever 13 which also is preferably formed of a die casting and provided with a pair of outwardly projecting arms 14 and 15 between which a roller 16 is rotatably mounted.
- 5 The dispensing head has formed therein a pair of bores or passageways 17 and 18 which receive therein a pair of washers 19 and 20. Fitting within the bores 17 and 18 respectively, are a pair of guide members 21 and 22 which have 10 formed thereon valve seats 23 and 24 against which seat the valves 25 and 26. Loosely fitting within the guide members 21 and 22 are a pair of valve actuating members 27 and 28 which are shaped in section, as shown most clearly in Fig. 15 21 and 22 and provided with communicating ports and bores to permit flow therethrough when the valves are opened. Fitting over the guide members 21 and 22 are a pair of flexible gaskets 29 and 30. The reference characters 31 and 32 designate a pair of nipples or collars which threadedly engage the dispensing head and hold the valves and associated parts in place, the nipples 31 and 32 each having an opening therein of such size as to receive therein the discharge end of the 25 dispensing nozzle of a siphon bottle. Secured in the lower ends of the dispensing head are a pair of nipples 33 and 34. Connected with the nipple 33 is a supply line 35 which connects with a suitable source of carbonated water. Connected with the nipple 34 is a supply line 36 which is connected 30 with a source of supply of carbon dioxide gas.
- The reference character 37 designates a siphon bottle of the usual construction which has applied thereto a closure member 38 which has formed 35 integral therewith a dispensing spout 39. The sockets or openings 40 and 41 are designed to fit over the end of the closure member of the siphon bottle. When it is desired to charge or re-charge a siphon bottle, the end of the dispensing nozzle 40 of the bottle is first placed within the fitting 31 in the position shown in Fig. 3. The arm 8 is then moved to engage the head member 9 with the upper end of the closure for the siphon bottle. In this position of the bottle the lever 13 will 45 assume the position shown in Fig. 3 with the roller 16 disposed above the lever 40 which serves to open the siphon bottle dispensing valve. To charge the bottle with carbonated water it is merely necessary to first squeeze the lever 13 to 50 move the lever 40 downwardly to open the siphon bottle dispensing valve and to simultaneously depress the arm 8 which forces the delivery end of the dispensing nozzle of the siphon bottle into engagement with the valve actuating member 27 to move the valve 25 away from its seat against the tension of a coil spring 42 which normally urges the water valve to closed position. When the valve 25 is opened, the carbonated water being 55 under pressure, will flow through the pipe 35 and thence through the siphon bottle dispensing nozzle to the interior of the bottle, the dispensing valve being open. It is customary to fill the dispensing bottle about three-fourths full. When this amount of carbonated water has been 60 delivered to the siphon bottle, the lever 13 is released and the arm 8 is then lifted upwardly. The dispensing valve being urged to its seat by a spring (not shown) is moved to closed position. The dispensing nozzle of the siphon bottle is then 65 placed within the nipple 32. The arm 8 is first depressed, and the lever 13 then moved to open the siphon bottle dispensing valve. In this position of the parts free gas under pressure will 70 flow through the pipe 36 and through the siphon bottle dispensing nozzle. This carbon dioxide gas 75

is under a pressure of about 125 pounds per square inch. The gas will flow into the bottle until the remaining space in the bottle is filled with gas at a pressure of the order of 125 pounds per square inch. Siphon bottles are usually constructed to withstand a pressure of 250 pounds per square inch, although it is contemplated that the siphon bottle be enclosed within a suitable cage or casing to prevent injury to the operator should the siphon bottle burst as a result of the high pressure. To release the siphon bottle, it is merely necessary to release the lever 13 and swing the arm 8 to the position shown in Fig. 1.

After these operations, the siphon bottle is about three-fourths full of carbonated water and the remaining space in the bottle is filled with carbon dioxide gas at a pressure of approximately 125 pounds per square inch. As the siphon bottle contains a considerable quantity of free gas under a substantial pressure, the water in the bottle will 15 tend to absorb an additional amount of gas when it is cooled to any substantial degree. This excess quantity of free gas also aids in dispensing the carbonated water from the siphon bottle at considerable pressure until all of the water is dispensed.

It will now be clear that we have provided an apparatus for charging siphon bottles which will accomplish the objects of the invention hereinbefore stated. It is of course to be understood that various changes may be made in the details of construction and arrangement of parts without departing from the spirit of the invention as the embodiment of the invention herein disclosed is to be considered merely as illustrative and not 30 in a limiting sense and that the invention is limited only in accordance with the scope of the appended claims.

Having thus described our invention, what we claim is:

1. An apparatus for charging a siphon bottle comprising a head for receiving and positioning the discharge spout of a siphon bottle in either of two positions, means for delivering carbonated water to said bottle through the discharge spout thereof in one position and means for delivering gas to said bottle through the discharge spout thereof in the other position, and a single lever for holding said bottle in either position.

2. An apparatus for charging a siphon bottle comprising a head for receiving and positioning the discharge spout of a siphon bottle in either of two positions, means for delivering carbonated water to said bottle through the discharge spout thereof in one position and means for delivering gas to said bottle through the discharge spout thereof in the other position, said means including a lever movable to engage the siphon bottle in either position.

3. An apparatus for charging a siphon bottle comprising a head for receiving and positioning the discharge spout of a siphon bottle in either of two positions, means for delivering carbonated water to said bottle through the discharge spout thereof in one position and means for delivering gas to said bottle through the discharge spout thereof in the other position, said means including a lever movable into engagement with the siphon bottle in either position, and means for opening the siphon bottle dispensing valve.

4. An apparatus for charging a siphon bottle comprising a head for receiving and positioning the discharge spout of a siphon bottle in either of two positions, means for delivering carbonated water to said bottle through the discharge spout thereof in one position and means for delivering

gas to said bottle through the discharge spout thereof in the other position, said means including a lever operable to hold the siphon bottle in either position and means carried by said lever for opening the siphon bottle dispensing valve.

5. In an apparatus for filling siphon bottles, the combination of a filling head having means for delivering either carbonated water or gas to the bottle through the discharge spout of the bottle, means for securing said spout in a position to be charged with carbonated water or in a position to be charged with gas and means operable in either position of said bottle to open the siphon bottle dispensing valve.

10. In an apparatus for filling siphon bottles, the combination of a filling head having valve controlled means for delivering either carbonated water or gas to the bottle through the discharge spout of the bottle, means for securing said spout in a position to be charged with carbonated water or in a position to be charged with gas, means operable in either position of said bottle to open the siphon bottle dispensing valve, and means operable by the spout of the siphon bottle for opening the carbonated water supply valve or the gas supply valve.

15. In an apparatus for filling siphon bottles, the combination of a filling head having means for delivering either carbonated water or gas to the bottle through the discharge spout of the bottle, means for securing said spout in a position to be charged with carbonated water or in a position to be charged with gas and means operable in either position of said bottle to open the siphon bottle dispensing valve, a pair of valves for controlling the supply of carbonated water and the supply of gas respectively, each of said valves being movable to open position by said spout.

20. An apparatus for charging siphon bottles comprising means for delivering carbonated water to a siphon bottle through the dispensing spout thereof in one position of said bottle, means for delivering gas under pressure to said bottle through said spout in another position of said bottle, and means for opening the siphon bottle dispensing valve in either position of said bottle.

25. In an apparatus for charging a siphon bottle with carbonated water and also with gas, the combination of means for holding the siphon bottle in a position to be charged with carbonated water through the discharge spout thereof or in a position to be charged with gas through the discharge spout thereof, and means for opening the siphon bottle dispensing valve in either of said positions.

30. In an apparatus for first charging a siphon bottle with carbonated water and then charging said bottle with a quantity of free gas comprising a pair of dispensing heads disposed immediately adjacent each other, each of said heads being shaped to receive therein the delivery end of the dispensing spout of the siphon bottle, a lever adapted for engagement with the siphon bottle in either of two positions, means for delivering carbonated water to said bottle in one position, means for delivering free gas to said bottle in the other position including valve means associated with each of said pair of dispensing heads and adapted to be engaged by said dispensing spout, said lever being operable to open said valves.

35. In an apparatus for first charging a siphon bottle with carbonated water and then charging said bottle with a quantity of free gas comprising a pair of dispensing heads disposed immediately

adjacent each other, each of said heads being shaped to receive therein the delivery end of the dispensing spout of the siphon bottle, a lever adapted for engagement with the siphon bottle in either of two positions, means for delivering carbonated water to said bottle in one position, means for delivering free gas to said bottle in the other position including valve means associated with each of said pair of dispensing heads and adapted to be engaged by said dispensing spout, said lever being operable to open said valves, and means carried by said lever for opening the siphon bottle dispensing valve to permit charging thereof.

40. In an apparatus for charging a siphon bottle first with carbonated water and then with free gas, the combination of a dispensing head having a carbonated water dispensing outlet and a gas dispensing outlet, means for connecting the dispensing spout of a siphon bottle with either of said outlets, and means for opening the siphon bottle dispensing valve in either position of said bottle.

45. In an apparatus for charging a siphon bottle first with carbonated water and then with free gas, the combination of a dispensing head having a carbonated water dispensing outlet and a gas dispensing outlet, means for connecting the dispensing spout of a siphon bottle with either of said outlets, means for opening the siphon bottle dispensing valve in either position of said bottle, a pair of valves for controlling the delivery of carbonated water and gas, respectively, and a lever for moving said siphon bottle to open either of said valves selectively.

50. In an apparatus for first charging a siphon bottle with carbonated water and then with gas, the combination of a dispensing outlet for carbonated water and a dispensing outlet for free gas disposed adjacent each other, means for connecting a siphon bottle with either of said dispensing outlets selectively including a single lever engaging said bottle in either position.

55. In an apparatus for first charging a siphon bottle with carbonated water and then with gas, the combination of a dispensing outlet for carbonated water and a dispensing outlet for free gas disposed adjacent each other, means for connecting a siphon bottle with either of said dispensing outlets selectively, and valve means for controlling each of said dispensing outlets operable by the movement of the siphon bottle, and a single lever for engaging said bottle in either position.

60. An apparatus for charging a siphon bottle first with carbonated water and then with a quantity of free gas comprising a pair of dispensing heads disposed immediately adjacent each other, each of said heads being shaped to receive therein the end of the siphon bottle dispensing spout, means connecting one of said heads with a source of supply of carbonated water, means connecting said other head with a source of supply of free gas, a valve in each of said heads for controlling the flow therethrough, means for connecting the siphon dispensing spout with either of said heads and means for opening the siphon bottle dispensing valve in either position of said bottle.

65. An apparatus for charging siphon bottles first with carbonated water and then with carbon dioxide gas comprising a fixture adapted to be secured to a rigid support, a pair of dispensing heads carried by said fixture, means connecting one of said heads with a source of supply of car-

bonated water, means connecting said other head with a source of supply of free gas, each of said heads having a valve therein for controlling the flow therethrough and being shaped to receive
5 therein the end of a siphon bottle dispensing spout, a post carried by said fixture and means carried by said post for connecting a siphon bot-

tle dispensing spout with either of said dispensing heads and means for opening the siphon bottle dispensing valve to permit filling thereof through said spout.
